CYLINDER CONTROL MECHANISM

Filed March 25, 1922

2 Sheets-Sheet 2

UNITED STATES PATENT OFFICE.

EDWARD F. DUDLEY, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

CYLINDER-CONTROL MECHANISM.

Application filed March 25, 1922. Serial No. 546,607.

To all whom it may concern:

Be it known that I, EDWARD F. DUDLEY, a citizen of the United States, residing at Oak Park, in the county of Cook and State of Illinois, have invented certain new and useful Improvements in Cylinder-Control Mechanism, of which the following is a specification.

This invention relates to printing presses 10 and more particularly to cylinder control mechanism therefor.

While this invention is not limited to a vertical type of printing press, it is disclosed in connection with such a printing press in which the type bed and the cylinder reciprocate vertically in opposite directions in a manner such that when the cylinder moves upwardly and the type bed moves downwardly, the cylinder is locked to its 20 driving mechanism and caused to rotate for causing a sheet of material carried thereby to receive an impression. However, when the movements are reversed, that is, when the cylinder is moved downwardly and the type bed upwardly, the cylinder is unlocked from its driving mechanism so that said cylinder does not rotate in its downward movement. While the cylinder normally rotates as it moves upwardly for giving a 30 sheet carried thereby an impression, it is desirable to prevent said cylinder from rotating during an upward movement if a sheet of material has not been fed to the cylinder or is not in proper front register with respect thereto.

Accordingly, one object of this invention is to provide simple, reliable and efficient means whereby the cylinder automatically will be prevented from being rotated in the 40 event that a sheet is not fed to the cylinder or a sheet is not properly registered with respect thereto.

Another object is to provide cylinder control mechanism in which the parts cooperate in an improved manner to meet the various requirements for successful commercial operation.

These and other objects are accomplished by means of the arrangement disclosed on the accompanying sheets of drawings, in which—

Figure 1 is a fragmentary front elevation

of a vertical type of printing press embodying my invention;

Figure 2 is an elevational view of a printing press cylinder embodying the invention;

Figure 3 is a fragmentary end elevation of the same cylinder;

Figure 4 is a sectional view of the cylinder taken in the plane of line 4—4 of Figure 2; and

Figure 5 is a fragmentary plan view of the cylinder showing the grippers, suction openings in the gripper bar, and a sheet of material being fed to the cylinder grippers.

The various novel features of the invention will be apparent from the following description and drawings, and will be particularly pointed out in the appended claims.

Referring to the figures of the drawings, it will be noted that the invention is illustrated in connection with a vertical type of printing press including a main frame 10 upon which is mounted the way frame including way frame members 11 and 12 in which the type bed, not shown, and the cylinder frame 13, are vertically slidably mounted in simultaneous reciprocation in opposite directions, a cylinder 14 being rotatably mounted in the cylinder frame 13.

This invention has to do primarily with cylinder control mechanism. In this connection it will be noted that the cylinder 14 is provided with a gripper bar 15 in which the grippers 16 are slidably mounted, each gripper normally being held closed by a spring 17 coiled around the shank of each gripper and interposed between the inner part of the gripper bar and a pin 18 in the shank of the gripper. The cylinder grippers 16 are opened by means of mechanism including operating fingers 19 mounted upon a rod 20 in the walls of the cylinder, one end of said rod 20 extending through one of the cylinder walls and having mounted thereon a lever 21 carrying a roller 22 which cooperates with two cams 23 and 24, the cam 23 being located at the upper part of the type bed so that when the roller 22 rides upon said cam 23 the grippers 16 are opened to release an impressed sheet of material preparatory to the latter being carried away from the cylinder by delivery

grippers (not shown). The cam 24 is located at the lower limit of movement of the cylinder 14 and has two cam portions 25 and 26. The upper cam portion 25 opens 5 the grippers near the end of the downward movement of the cylinder for the purpose of receiving a sheet of paper fed to the cylinder, and the lower cam portion 26 of the cam 24 permits the roller 22 to ride downwardly thereon for permitting the grippers to close upon the sheet of material fed to the cylinder. At first blush it would seem that the roller 22 in the next upward movement of the cylinder would engage the 15 lower cam portion 26, causing the grippers again to open and release the sheet of paper before it received an impression. However, such occurrence is avoided by reason of the fact that the cylinder rotates in a counter-clockwise direction, as viewed in Figures 3 and 4, for carrying the roller 22 away from the cam 26 during the upper vertical impression movement of the cylinder.

In connection with the rotative driving 25 movement of the cylinder a gear 27 is provided at one end of the cylinder, and it is loosely mounted with respect to the cylinder and the parts thereof, so that it is possible for the gear 27, to be rotated while the cylinder 30 may not be rotated. The gear 27 is actuated during its upward and downward movement with the cylinder by meshing with a rack 28 carried by the type bed. Secured to or formed integrally with the gear 35 27 is a ratchet wheel 29 having a single slot 30 which is adapted to receive the hooked end 31 of a pawl 32 mounted upon a shaft 33 carried by the cylinder. This shaft has surrounding it a coiled spring 34, 40 one end of which is anchored to a wall of the cylinder and the other end of which is anchored to a collar 35 secured to the shaft in a manner such that the pawl is yieldably held against the ratchet member 29 and, as a 45 result thereof, at any time that the slot 30 is presented to the hooked portion 31 of the pawl 32 such pawl enters said slot for locking the cylinder to its driving mechanism for rotating said cylinder.

Attention is called to the fact that the slot 30 is provided with a straight driving wall 36 which is adapted to engage a corresponding front wall 37 of the pawl for positively driving the cylinder in a counterclockwise direction as viewed in Figure 4. The other wall 38 of the slot 30 is inclined, as is also the corresponding wall 39 of the pawl 32, whereby the pawl may be forced out of the slot 30 of the ratchet wheel 29 when the cylinder 60 has reached its upper limit of movement preparatory to said cylinder moving vertically downwardly without rotating. However, the inclination of the walls 38 and 39 of the slot 30 and pawl 32, respectively, 65 are sufficiently abrupt to prevent the cyl-

inder running away from the gear during their rotative movements.

In connection with the control mechanism for the cylinder, attention is called to the fact that secured to the shaft 33 is a disk 40 70 having a single notch 41 engaged by a pawl 42 secured to one arm 43 of a bell crank lever 44 carried by any suitable support 45, the other arm 46 of the bell crank lever being connected to a rod 47 in turn operatively connected to a diaphragm 48 of a casing 49 forming part of a fluid pressure system. The interior of said casing beyond the diaphragm 48 is connected to a source of vacuum through a tube 50, said casing 80 49 also having extended therefrom a plurality of tubes 51 and 52 which are operatively connected with two series 53 and 54 of suction openings extending through the gripper bar 15. At the time that the cylinder is at its lower limit of movement preparatory to receiving a sheet of material, the suction pump is in communication or is cut into communication with the diaphragm chamber 49, so that suction is exerted downwardly through the two series 53 and 54 of openings in the gripper bar and through the tubes 51 and 52 and diaphragm chamber 49 and tube 50. If the openings 53 and 54 are left uncovered at such time, it is apparent that the flow of air through the diaphragm chamber 49 will have no affect upon the diaphragm and, accordingly, will not transmit any movement to the bell crank lever 43 and accordingly the pawl 32 will be held or locked out of operative relationship with respect to the ratchet wheel 29, so that if no sheet of paper is fed to the cylinder, or if the sheet of paper fed to the cylinder does not cover the openings 53 and 54 100 105 the cylinder will not become locked to its rotative or driving mechanism. As a result, the cylinder on its next upward movement and under the conditions stated, will not rotate. On the other hand, if the suction openings 53 and 54 in the gripper bar were closed by a sheet of material 55 which is fed to the cylinder and registered with respect thereto, it is apparent that the diaphragm 48 would be moved into the 110 chamber 49, drawing the pawl 42 away from the disk 40, thereby releasing the pawl 32 to permit it to pass into the slot 30 in the disk 29 when they come into register with each other, hereby resulting in the cylinder 115 120 125 130 135 140 145 150 155 160 165 170 175 180 185 190 195 200 205 210 215 220 225 230 235 240 245 250 255 260 265 270 275 280 285 It is apparent, therefore, that the rotation of the cylinder during its upward movement is dependent upon and controlled by a sheet of material being registered with respect to the cylinder.

It is my intention to cover all modifications of the invention falling within the spirit and scope of the following claims.

I claim:

10. 1. In a printing press, the combination of a cylinder, means for rotating said cylinder, and means whereby the rotative movement of said cylinder depends upon the proper registration of a sheet of material relative to said cylinder.

15. 2. In a printing press, the combination of a cylinder, means for actuating said cylinder, and means whereby the actuation of said cylinder depends upon the proper registration of a sheet of material relative to said cylinder.

20. 3. In a printing press, the combination of a cylinder, means for rotating said cylinder, and control means carried by said cylinder operative in accordance with registration conditions of a sheet of material with respect to said cylinder for controlling the rotative movement of the latter.

25. 4. In a printing press, the combination of a cylinder, driving means therefor, and fluid pressure means responsive to registering conditions of a sheet of material with respect to said cylinder for controlling the driving relationship between said driving means and cylinder.

30. 5. In a printing press, the combination of a cylinder, driving means therefor including a ratchet member and a pawl, and means for controlling the driving connection between said ratchet and pawl dependent upon the proper registration of a sheet of material with respect to said cylinder.

35. 6. In a printing press, the combination of a cylinder, driving means therefor including a ratchet and pawl, and fluid pressure means controlling the connection between said ratchet and pawl operable in accordance with proper registration of a sheet of material with respect to said cylinder.

40. 7. In a printing press, the combination of a cylinder having a gripper bar and grippers, driving means for said cylinder, and means for controlling the driving relationship between said driving means and cylinder dependent upon the reception of a sheet of material between said gripper bar and grippers and the proper registration of said sheet at said grippers.

45. 8. In a printing press, the combination of a cylinder having gripper bar, driving means for said cylinder, and fluid pressure means associated with said gripper bar whereby the driving relationship between said driving means and cylinder is dependent upon the feeding of a sheet of material to said gripper bar and the proper registration of said sheet at the gripper bar.

50. 9. In a printing press, the combination of a cylinder having a gripper bar with fluid pressure openings therein, driving means for said cylinder, and means for controlling the driving relationship of said means and cylinder depending upon a sheet of material being placed completely over the openings in said gripper bar.

55. 10. In a printing press, the combination of a cylinder having gripper mechanism, driving means for said cylinder, and a fluid pressure diaphragm operatively associated with said gripper mechanism and said driving means for controlling the driving relationship between said driving means and cylinder dependent upon the reception of a sheet of material by said gripper mechanism and the proper registration of said sheet at said gripper mechanism.

60. 11. In a printing press, the combination of a cylinder, gripper mechanism therefor having fluid pressure openings associated therewith, driving mechanism for said cylinder, and a fluid pressure diaphragm operatively associated with said gripper mechanism for controlling the driving relationship between said driving means and cylinder in a manner such that when a sheet of material does not cover said fluid pressure openings the cylinder will not be driven and if said fluid pressure openings are covered said cylinder will be driven.

65. 12. In a printing press, the combination of a cylinder, gripper mechanism therefor having fluid pressure openings associated therewith, means for rotating said cylinder, and a fluid pressure diaphragm operatively associated with said gripper mechanism for controlling the driving relationship between said rotating means and cylinder in a manner such that when a sheet of material does not cover said fluid pressure openings the cylinder will not be rotated and if said fluid pressure openings are covered said cylinder will be rotated.

Signed at Chicago, Illinois, this 2nd day of March, 1922.

EDWARD F. DUDLEY.
